UNITED STATES PATENT OFFICE.

HERBERT R. BLISS, OF NIAGARA FALLS, NEW YORK, ASSIGNOR TO BLISS CONTAINERS, INC., OF NIAGARA FALLS, NEW YORK, A CORPORATION OF NEW YORK.

SHIPPING CASE.

Application filed June 13, 1924. Serial No. 719,715.

This invention relates to shipping cases constructed of fibre board or equivalent material. It is the object of the present invention to afford a shipping case which is especially adapted for the transportation of heavy articles, such as automobile bumpers, etc. Articles of this kind present a very heavy end thrust on the end panels of the case. The ordinary fibre shipping case is ill adapted for shipping hardware of this kind, for while it has been possible to construct ends of plural thickness the seams have but one thickness and are easily broken. It has been proposed to provide a shipping case with wooden ends, etc., to take the end thrust, but cases so constructed are open to obvious disadvantages in that it has never been possible to join wood ends with ordinary fibre board box blanks, as the wood being very rigid, transmits a shock to the fibre board and splits same at the jointure. Such a box is no stronger than the joints that connect it to the sides of the case.

It is the object of the present invention to provide a shipping case that can be constructed of a single blank of fibre board or equivalent material and which results in no waste of material, and which further provides plural seams and plural joints to withstand the heavy end thrust of bumpers or other heavy hardware.

Referring to the drawings:

Fig. 1 is a plan view of the blank.

Fig. 2 shows the completed case.

Fig. 3 shows the blank partly folded up.

Fig. 4 shows the same blank further folded up.

Fig. 5 is a section on the line 5—5 of Fig. 2.

Fig. 6 is a section on the line 6—6 of Fig. 2.

Fig. 7 is a section on the line 7—7 of Fig. 6.

Figs. 8 and 9 are detail perspective showing how the seams are taken.

Fig. 10 is a fragmentary perspective showing how the case is sealed.

Fig. 11 is a section on the line 11—11 of Fig. 10.

Referring to Fig. 1, the blank for a

bumper case is relatively long and narrow and is scored to form a bottom wall *a*, two side walls *b* and *c*, and two cover wings *d* and *e*. The blank is also scored and slotted to provide end panels *f* which are joined only to the ends of the bottom wall and supplementary end panels *g*, preferably one at the end of each side wall. Joined at the sides of each of these supplemental end panels is a cover flap *h*. These cover flaps are continuations of the cover wings but are divided therefrom by slots. Each of the supplemental end panels is provided with a corner flap *j*; each of the cover flaps is provided with a reinforcing flap *i*, while these corner and reinforcing flaps *j* and *i* all line up along the ends of the blank. The end panels *f* have sufficient length preferably to extend out to the end edges of the blank.

The way the various elements are laid out in the blank as shown in Fig. 1, the width of the side walls is of course equal to the depth of the end wall when these dimensions are the same, and the layout is nicely balanced as in Fig. 1, so that the width of the supplemental end panels *g* plus the corner flaps *j* is just equal to the depth of the main end panels *f*; consequently there is no waste of material whatever. However as the vertical seams in the assembled case are the main ones necessary to be reinforced the length of the end panels are necessarily the width of the case so that the corner flaps will come into the desired position on the vertical seams.

Referring to Fig. 3, it will be seen how the parts are folded up. The side wall *c* is folded up with respect to the bottom wall *a* and the supplemental end panels *g* carried by the side wall *c* are turned in, as are also the corner flaps *j*, attached to such supplemental end panels. The cover flap *h*, together with its reinforcing flap *i* can be turned in at the top.

Next referring to Fig. 4, the other side wall *b* may be folded up and the supplemental end panel *g* folded in on the inside of the main end panel *f* or on the outside—this is optional. As shown in Figs. 4 and 2, the main end panel is on the outside. The

corner flap *j* fits inside of the side wall *c*. An anvil may now be run down inside the case at each corner and the side walls of the case wire-stitched to the corner flaps *j* and the three end panels at each end stitched together on the ends of the case, as shown in Fig. 8.

The above arrangement provides three fibre end panels at each end of the case and 10 provides two vertical wire-stitched seams at each vertical corner of the case. This obviously makes the case of extreme durability against end thrust.

The cover flaps *h* which are folded in at 15 the top under the cover wings provide a double reinforcing structure at the top of the case near the ends. Each one of these flaps is provided with a reinforcing flap *i* that is tucked in the inside of the case to 20 further reinforce it whenever the dimensions permit; otherwise they lie flush. The cover wings are then folded over and are shown in the drawings of such width as to form a complete overlap, but this overlap can be reduced 25 to save material. The result is that the top of the case has two thicknesses of fibre board running the entire length, while at the ends where the strain is greatest, there are three 30 thicknesses of fibre board. These two cover wings may be stitched together by the insertion of the blade anvil, as shown in Fig. 10. The cover flaps themselves may be 35 stitched together before the case is sealed, as shown in Fig. 4. However, this is simply optional with the shipper. Where they are stitched together as shown in Fig. 4, this adds two more seams which tend to resist any end thrust which is calculated to tear the three end panels apart.

40 As stated the main end panel *f* may be on the outside. However, it may also be on the inside or in the middle. However, this main end panel may be long or short according to the dimensions of the box, in which event 45 it is better to have it in the middle.

What I claim is:

1. In a shipping case for the purpose specified, a blank which is scored and slotted to provide bottom, side walls, cover wings and 50 end panels provided with perpendicularly folded corner flaps, the same being arranged to be folded up and fastened together along the entire flap to provide two vertical seams at each vertical end corner.

55 2. A shipping case for the purpose specified, having a single blank scored and slotted to provide a bottom wall, two side walls and a cover wing, a plurality of end panels with corner flaps, the same arranged to be folded up and fastened together to provide a plural 60 ply end structure with the corner flaps folded perpendicularly and stitched to the side walls to form a reinforcing seam for the vertical end corners of the box.

3. A shipping case for the purpose specified, having a single blank scored and slotted to provide a bottom wall, two side walls, a cover wing and a plurality of end panels, some of the end panels being provided with corner flaps, the same being folded up and 65 fastened together to provide a plural ply end structure, and the corner flaps turned over at right angles and stitched to the end walls while the end panels are stitched together to provide two vertical seams at each vertical 70 corner at the end of the case.

4. In a shipping case for bumpers or other heavy hardware, a rectangular blank of relatively long and narrow proportions, with substantially straight ends creased longitudinally and creased cross-wise near the ends, and slotted from such cross crease to the end in continuation of two of the center creases, whereby two side walls, a bottom wall, and cover wings, and at each end of the blank 80 three end panels, two with one corner flap each are afforded, the said end panels arranged to overlap when the blank is folded up to provide a three ply end, the said three end panels being each united to the other to resist the breaking down of the box when the same has been built up.

5. A fibre shipping case for the purpose specified, comprising a single blank slotted and scored to form two side walls, bottom 95 wall, and a cover wing, each of the side and bottom walls provided with end extensions in the blank forming end panels and the blank adjacent the cover wing provided with end 100 adjacent portions forming cover flaps, and both the cover flaps and some of the end panels provided with extended and scored portions forming respectively reinforcing flaps and corner flaps, the same all arranged to fold up and be fastened together to give a three-ply end structure with overlapping cover flaps at the top of the case near the ends, having tucked-in reinforcing flaps and to provide corner flaps which may be stitched to the adjoining side walls to provide additional reinforcement for the vertical corners at the 105 ends of the case.

6. A fibre shipping case for the purpose specified, constructed of a single blank comprising a blank structure slotted and scored to provide a bottom wall, two side walls and two cover wings, each of which is in the blank provided at each end with an adjacent portion forming in the aggregate at each end 115 three end panels, two of which are provided with corner flaps and two cover flaps, each of the latter being provided with a reinforcing flap, the said elements arranged to be folded and fastened together to form a box having a 120 three-ply end structure which may be fastened together, and the corner flaps turned in at right angles and engaging the side walls to provide double seams at each vertical cor- 125

ner at each end of the case, and the cover flaps turned in in overlapped relation while the reinforcing flaps are tucked in.

7. A shipping case for the purpose specified, having a single blank scored and slotted to provide a bottom wall, two side walls, and a cover wing, a plurality of panels at each end of the blank provided with corner flaps

the same arranged to be folded up to provide a plural ply end structure with the corners 10 folded up perpendicularly and stitched to the side walls.

In testimony whereof I have affixed my signature.

HERBERT R. BLISS.
